[57] **ABSTRACT**

The relative current in a pair of inductive loads is rapidly varied by maintaining a current in each load, so that when current is removed from one the rapid decay of current in that coil permits a substantial relative current differential since the other load need not rise from zero current due to the current pre-established therein. To further enhance the rapid current differential a choke in series with a low voltage supply provides a constant current source so that a large voltage spike is generated when the current goes to zero in one load thus enhancing the current buildup in the other load.

METHOD AND CIRCUIT FOR DRIVING INDUCTIVE LOADS

CROSS-REFERENCES TO RELATED APPLICATIONS

The present invention is particularly adapted for use in the microfilm printer described in U. S. Pat. application Ser. No. 864,036, filed Oct. 9, 1969.

BACKGROUND OF THE INVENTION

The invention relates to a circuit and method for driving a pair of inductive loads and more particularly to a circuit and method for driving the stator coil of a pair of magnetic particle clutches used to control a drive shaft.

A magnetic particle clutch is a device for clutching and/or braking a rotatably shaft. The control medium in the device is a dry magnetic particle compound contained within the annular gap between the continuously rotating input member and the low inertia output member. When the stator coil is energized, a magnetic field traverses the gap, binding the particles together in the manner of bar magnets, along the lines of flux. These "chains" of magnetic particles provide the coupling between the input and output members. Under a slip condition, these chains shear at their centers, leaving an immobile layer next to the input and output members. The strength of the coupling is proportional to the stator excitation current.

Particle clutches exhibit a relatively slow torque buildup, typically greater than 2 milliseconds. However, it has been observed that these same clutches lose torque rapidly when the steady state current is disrupted, generally being an order of magnitude faster than torque buildup.

One application requiring the rapid starting and stopping of a shaft rotation is the capstan of a high-speed microfilm printer. In that application a film is moved to successive line locations and rapid start/stop times are necessary for the film movement as described in the referenced application. Other applications may readily occur to those of ordinary skill in the art including the control of tape deck capstans and machine control in industrial processes.

Rapid starting and stopping of an incremental drive capstan, as in a high speed microfilm printer, is provided by a pair of matched magnetic particle clutches. One is connected to operate as a clutch to drive the capstan while the other is connected as a brake to stop it.

Normally high voltage power supplies are required to drive high inductance circuits when fast current rise time is required. Thus in order to achieve a rapid start/stop time using a pair of magnetic particle clutches, one would expect to use a high voltage supply to drive the stator coils.

SUMMARY OF THE INVENTION

The present invention overcomes the problems in achieving rapid start/stop times by providing an electronic circuit and method wherein acceleration or deceleration of the drive shaft is accomplished with torque previously established by decaying the torque of the opposing member. Thus in the steady-state stop condition the drive device is maintained at a given

torque level but less than the torque level of the braking device. In order to initiate starting, the braking torque is allowed to decay to zero, and does so rapidly due to the characteristics of the magnetic particle clutch.

Thus the drive clutch torque is left to effect rapid start. After a brief starting period a brake bias torque, less than the drive torque in the steady-state stop condition, is applied so that the transition from running to stop may be made in the same manner. Thus to stop, the driving torque is allowed to rapidly decay leaving the brake bias torque to which further braking torque is added, the sum of the established brake bias torque and the rising further brake torque causing a rapid stopping of the shaft. After a brief stopping period, the drive torque, less than the total brake torque, is re-applied so that the cycle may be repeated with the same starting conditions.

To further enhance the start and stop times of the arrangement, a choke is placed in series with the low voltage power supply to provide a constant current source. The characteristics of a constant current source and the two inductive loads is used to provide high voltage spikes at the start and stop times to enhance the current flow in the active clutch member to provide greater starting and stopping torque.

These and other advantages of the present invention will become apparent as the following description is read and understood.

BRIEF DESCRIPTION OF THE DRAWINGS

FIG. 1 is a schematic circuit diagram showing the electronic portion of an embodiment of the present invention.

FIG. 2 (a-l) is a series of graphical representations showing waveforms useful in understanding the circuit of FIG. 1.

FIG. 3 is a cross-sectional view taken through the center of a capstan drive employing magnetic particle clutches of the type adapted to be driven by the circuit of FIG. 1.

DESCRIPTION OF THE PREFERRED EMBODIMENTS

Referring now to FIG. 1 of the drawings, wherein a schematic diagram of an embodiment of the invention is shown. A choke L_c is connected between a voltage source $+V$ and a junction point J_1 . A pair of parallel circuits is connected between junction point J_1 and ground. The first circuit includes a series connection of an inductor L_1 , a resistor R_1 and the collector and emitter of an NPN transistor Q_1 . The base e of transistor Q_1 receives a signal S_1 . The second circuit includes the series connection of an inductor L_2 and two further sub-circuits in parallel. The first circuit includes a series connection of a resistor R_2 and the collector and emitter of an NPN transistor Q_2 . The base of Q_2 receives a signal S_2 . The second sub-circuit includes a resistor R_3 and the collector and emitter of an NPN transistor Q_3 . The base of Q_3 receives a signal S_3 .

A clamping diode - zener diode arrangement is provided as a practical expediency to protect transistors Q_1 , Q_2 and Q_3 from voltages at their collectors that may exceed their ratings and thus damage the transistors. The cathodes of diodes D_1 , D_2 , and D_3 are connected together to the cathode of zener diode Z_1 . The anode of

Z_1 is grounded, and the anodes of diodes D_1 , D_2 , and D_3 are connected to the respective collectors of Q_1 , Q_2 and Q_3 .

Inductors L_1 and L_2 are the stator windings of magnetic particle clutches. Both clutches are mounted on a common shaft for the film drive. The clutch of inductor L_1 is mounted to provide clutch action and the clutch of inductor L_2 is mounted to provide braking action.

Referring now also to FIG. 2, wherein various waveforms are shown to assist in the understanding of the operation of the circuit of FIG. 1. In the steady-state condition prior to time t_0 all three transistor Q_1 , Q_2 and Q_3 are in saturation and the clutch coil current I_1 (through clutch inductor L_1) is less than the brake coil current I_2 (through brake inductor L_2). I_2 exceeds I_1 because the resistance values of R_1 , R_2 and R_3 are chosen so that the parallel combination of R_2 and R_3 is less than R_1 . In an exemplary embodiment, R_1 and R_2 are 12.5 ohms and R_3 is 25 ohms. The resistance of inductors L_1 and L_2 is small and may be ignored. The value of $+V$ is, for example, 24 volts. This voltage is also present at J_1 prior to t_0 . The diode clamping protection circuit D_1 , D_2 , D_3 and Z_1 may also be ignored prior to t_0 . In fact, it may be ignored throughout the operation for the purposes of understanding the inventive concept.

At time t_0 , the time at which the start of film motion is desired, the brake bias signal S_3 and the brake signal S_2 are pulsed negative sufficiently to cutoff Q_3 and Q_2 , respectively. I_2 rapidly becomes zero, but the current I from choke L_c cannot change instantaneously, i.e.: L_c acts as a constant current source. I_1 must therefore increase accordingly, but since I_1 is flowing through an inductive load L_1 that resists rapid current changes the voltage at J_1 necessarily increases substantially to drive the additional current through L_1 . Diodes D_2 and D_3 conduct to limit the collectors of Q_2 and Q_3 to the zener voltage V_z in order to protect the collectors from the high voltage spike at J_1 . FIG. 2 (e, f & g) show the currents I_1 , I_{R_2} and I_{R_3} for a perfect constant current source. I_2 is, of course, equal to I_{R_2} plus I_{R_3} and FIG. 2(i) shows the currents in an actual circuit. The high voltage available at J_1 at t_0 causes the current I_1 in L_1 to rise rapidly thus effecting fast clutch action in combination with the rapid cessation of current I_2 in the brake. Also, since I_1 was already at a level above zero prior to t_0 , the high energization of L_1 was further facilitated.

At time t_1 , a relatively non-critical time after t_0 , chosen to be at least long enough for I_2 to reach zero and I_1 to reach maximum, the brake bias current is turned on by removal of the negative signal from the base of Q_3 , causing Q_3 to saturate. Since R_3 is about twice the resistance of R_1 , I_{R_3} (equal to I_2) will be less than I_1 . The voltage J_1 drops somewhat since some current is now flowing into L_2 . I_1 also drops the amount that I_2 increases, since I must remain substantially constant. Q_2 remains cutoff.

At time t_2 the film motion is to be stopped; Q_3 controlling brake bias is allowed to remain in saturation and the negative signal from the base of Q_2 is removed switching it from cutoff to saturation. Simultaneously the base of Q_1 is pulsed negatively driving it to cutoff. Thus the clutch current I_1 must fall to zero and I_2 is allowed to rise since Q_2 and Q_3 are saturated. As at t_0 , there is a high voltage spike at J_1 , because the current I

cannot change instantaneously. I_2 therefore rises rapidly to its maximum value and I_1 falls to zero resulting in maximum braking and minimum clutch action. The drive shaft rotation is therefore rapidly stopped.

At time t_3 , also a non-critical time, sufficiently long after t_2 to permit I_2 to reach its maximum value and I_1 to drop to zero, the circuit is returned to its steady state motion stopped condition. Q_2 and Q_3 are already in saturation and Q_1 is allowed to saturate by removal of the negative signal at its base. I_2 must therefore drop as I_1 increases from zero to its steady state value.

Referring now to FIG. 3, a drive mechanism for a capstan 50 employing a pair of magnetic particle clutches is shown. The clutches may be driven using the circuit of FIG. 1. The drive mechanism for the incremental drive capstan 50 includes a shaft 120 rotatably mounted by means of a bearing 122 in a rigid housing 124 which is attached to the frame 14 by screws 126. The other end of shaft 120 is rotatably mounted in a bearing 128 which is supported inside of a sleeve 130 which is rigidly attached to the frame 14. The sleeve 130 forms part of a brake assembly 132 which is sold by the Power Equipment Division of Lear Siegler Industries under the trademark "FASTE" magnetic particle clutch Model 97015-012.

This brake 132 includes a casing 134 rigidly attached to the sleeve 130 and a central sleeve 136 which is rotatably attached to the frame 134 by bearings 128 and 138. A chamber 140 is provided between the casting 134 and sleeve 136, and a cylindrical blade 142 rigidly attached to the sleeve 136 extends into the center of this chamber adjacent to sleeve 130 and casting 134. The remainder of the chamber 140 is filled with ferromagnetic particles which, in the absence of a magnetic field are in a fluid state. An electromagnetic coil 144 (corresponding to L_2 of FIG. 1) surrounds the chamber 140, and upon the application of electric current to the coil 144, the ferromagnetic particles in chamber 140 solidify to rigidly connect the sleeve 130 to the sleeve 136. The sleeve 136 is keyed to shaft 120 by set screws in apertures 146 so that the application of an electrical current to the coil 144 applies a brake between the shaft 120 and the frame 14.

A second identical "FASTE" clutch 148 is mounted with its center sleeve keyed to the shaft 120 by a set screw in aperture 150, and the outer sleeve 130a of the clutch 148 carries a pulley 152 over which the belt 116 is entrained. The application of electrical current to the coil 149 (corresponding to L_1 of FIG. 1) of clutch assembly 148 establishes a rigid connection between the drive belt 116 and shaft 120 so that incremental drive capstan 50 is driven by motor 112.

It will be apparent to those of ordinary skill in the art that many modifications of the disclosed embodiments are possible without departing from the spirit and scope of the invention. For example, switching devices other than transistors may be employed and protective schemes other than the diode-zener clamping circuit disclosed may be used. And the invention is not limited to use in controlling capstan drives. The invention is therefore to be limited only by the scope of the appended claims.

I claim:

1. A circuit for providing a rapid change in the relative current between a pair of inductors comprising means for supplying a substantially constant current,

- a first circuit including a first of said inductors, first resistance means, and first switch means in series with said means for supplying a substantially constant current, 5
- a second circuit including a second of said inductors and a parallel circuit in series with said means for supplying a substantially constant current, said parallel circuit including a first and second series circuit, said first series circuit including second resistance means and second switch means and said second series circuit including third resistance and third switch means, said first and second resistance means having substantially the same resistance and said third resistance means having a resistance substantially equal to the sum of said first and second resistance means, whereby closing said first, second and third switch means maintains the current in said second inductor greater than the current in said first inductor, opening only said second and third switch means provides a rapid increased in said first inductor current relative to said second inductor current, and opening only said first switch means provides a rapid increase in said second inductor current relative to said first inductor current. 10
2. A circuit according to claim 1 wherein said first, second, and third switch means are transistors, connected to provide a closed circuit between the respective emitters and collectors when said transistors are in saturation and to provide an open circuit between the respective emitters and collectors when said transistors are cutoff. 15
3. A circuit according to claim 1 wherein said first and second inductors are the stator coils of first and second magnetic particle devices, respectively. 20
4. A circuit connectible to a DC voltage source supplying a substantially constant current for rapidly switching the relative current in inductive loads in response to control signals comprising 25
- first inductive load means,
second inductive load means,
first inductive load control means connected to said first inductive load means and to said DC voltage source for controlling the current in said first inductive load; 30
- second inductive load control means connected to said second inductive load means and to said DC voltage source for controlling the current in said second inductive load; 35
- said first and second inductive load control means responding to control signals in a steady state stop mode of operation to provide a predetermined first inductive load current and a predetermined second inductive load current and greater than said first inductive load current, and responding to control signals in a start mode of operation to reduce said second inductive load current to substantially zero, and responding to control signals in a steady state start mode of operation to re-establish said second inductive load current at a level less than said first inductive load current, and responding to control signals in a stop mode of operation to reduce said first inductive load current to substantially zero. 40
5. A current according to claim 4 wherein said first inductive load control means comprises 45

- first resistance means and first switch means responsive to a first control signal, said first inductive load, said first resistance means and said first switch means connected in series. 5
6. A circuit according to claim 5 wherein said second inductive load control means comprises 10
- a first branch circuit comprising second resistance means and second switch means responsive to a second control signal, said second inductive load, said second resistance means and said second switch means connected in series, and
a second branch circuit comprising a third resistance means and third switch means responsive to a third control signal, said second inductive load, said third resistance means and said third switch means connected in series. 15
7. A circuit according to claim 6 wherein said switch means comprises solid-state switching device means for providing open or closed circuits in response to control signals. 20
8. A circuit according to claim 7 wherein said first resistance means has a resistance close to the resistance of said second resistance means and said third resistance means has a resistance close to the sum of the resistance of said first and second resistance means. 25
9. A circuit according to claim 7 wherein said solid-state switching device means comprise transistors each having an emitter, base and collector, said emitters and bases providing switching action as the base voltage is controlled to vary said transistors between cutoff and saturation. 30
10. A circuit according to claim 9 wherein said DC voltage source is connectable between the junction of said load inductors and said switching transistors. 35
11. A circuit according to claim 10 wherein said inductive loads are the stator coils of first and second magnetic particle devices. 40
12. A circuit for providing a rapid change in the relative current between a pair of inductors comprising 45
- a first load inductor,
a second load inductor,
a choke,
means for connecting one end of said load inductors together through said choke to a first polarity of a source of DC voltage, 50
- first resistance means,
means for connecting the second end of said first load inductor to said first resistance means, first switch means connected between said first resistance means and the second polarity of said source of DC voltage, 55
- second resistance means,
means for connecting the second end of said second load inductor to said second resistance means, second switch means connected between said second resistance means and the second polarity of said source of DC voltage, 60
- third resistance means,
means for connecting the second end of said second load inductor to said third resistance means, third switch means connected between said third resistance means and the second polarity of said source of DC voltage. 65
13. A circuit according to claim 12 wherein said switch means comprise first, second and third 70

transistors each having a base, emitter and collector, the emitter and collector of each transistor providing the switching action.

14. A circuit according to claim 13 further comprising a zener diode having one side connected to said polarity of the DC voltage three diodes having a first side thereof connected to the other side of zener diode,

and the remaining side of said diodes connected to each of said transistors, respectively.

15. A circuit according to claim 13 wherein said first and second load inductors are the stator coils of first and second magnetic particle devices, respectively.
